UNITED STATES PATENT OFFICE.

LOUIS M. SCHNITZER AND LEON GARROWAY, OF BROOKLYN, AND NATHAN GELFMAN,
OF NEW YORK, N. Y.

DESIGN FOR A TRAY.

61,381.

Specification for Design.

Patented Aug. 15, 1922.

Application filed December 3, 1921. Serial No. 519,775. Term of patent 3½ years.

To all whom it may concern:

Be it known that we, LOUIS M. SCHNITZER, LEON GARROWAY, and NATHAN GELFMAN, citizens of the United States, residing, respectively, at the borough of Brooklyn, city of New York, county of Kings, and State of New York, of the borough of Brooklyn, city of New York, county of Kings, and State of New York, and of the borough of Bronx, city of New York, county of Bronx, and State of New York, have jointly invented a new, original, and ornamental Design for Trays, of which the following is a specification, reference being had to the accompanying drawing, forming part thereof.

Fig. 1 is a top plan view of a tray showing our new design, Fig. 2 represents a front elevation of Fig. 1 and Fig. 3 is a section of Fig. 1 on the line 3, 3.

We claim:

The ornamental design for a tray, as shown.

Signed at the borough of Brooklyn, city of New York, in the county of Kings and State of New York, this 21st day of November, 1921.

LOUIS M. SCHNITZER.
LEON GARROWAY.
NATHAN GELFMAN.
